INK MARKING INSTRUMENT

Anthony J. Randolph, 321 Pearsall Ave., Ridgewood, N.J.

Filed Dec. 22, 1961, Ser. No. 68,034

Term of patent 14 years

(Cl. D74—17)

FIG. 1 is a front elevational view of an ink marking instrument therefore showing my new design;

FIG. 2 is a top plan view thereof; and

FIG. 3 is an exploded fragmentary elevational view thereof.

The dominant features of my design shown herein in solid lines reside in the combination on the marking device disclosed of the particular flexible cap member which conformably engages with the dispensing neck portion of the container and which flares outwardly toward the top and terminates in a shallow peak at the top, all as shown.

I claim:

The ornamental design for an ink marking instrument, substantially as shown and described.
